OIL BURNING EQUIPMENT

George P. Haynes, East Rockaway, N. Y., assignor
to Todd Combustion Equipment, Inc., New
York, N. Y., a corporation of New York

Original application July 3, 1936, Serial No. 88,736.
Divided and this application December 31, 1936,
Serial No. 118,623

2 Claims. (Cl. 158—2)

This invention relates generally to oil burning equipment, and is a division of my co-pending application, Serial No. 88,736, filed July 3, 1936.

While not so limited, my invention is intended particularly for use on marine vessels, wherein it is proposed to bulkhead the fire room thus dividing the latter into a boiler compartment and an operators' compartment, said bulkhead being air tight and water tight, and hence, one of said compartments is protected in case the other is flooded with water or filled with gases.

As will presently appear, oil burning equipment, including burner and air register units, is positioned between the boiler front and the bulkhead and suitable means is provided to provide an air tight and water tight connection of the burner equipment with relation to said bulkhead.

In that it is frequently necessary to remove the burner tube from its jacket, it is of vital importance that the passage within said jacket be closed in order to prevent the flow of gases from the boiler or boiler compartment to the operators' compartment, or the passage of water from the operators' compartment to the boiler and boiler compartment in the event said operators' compartment should be flooded.

It is therefore, the object of the invention to provide means adapted to automatically close the burner jacket against pressure flow in either direction when said burner tube is removed, which otherwise would leave an open passage through said bulkhead.

Other features and advantages of my invention will hereinafter appear.

In the drawings:

Figure 1 is a front elevation showing a bulkhead in a fire room with the burner portions projecting forwardly thereof.

Fig. 2 is a sectional view, taken on the line 2—2 of Fig. 1, showing the burner equipment mounted on the boiler front plate and the bulkhead.

Fig. 3 is a sectional detail of the rear portion of the burner equipment with the burner tube removed and the burner jacket closed.

Referring now more in detail to the accompanying drawings, wherein like characters of reference denote similar parts throughout the several views, let 1 indicate a bulkhead which extends transversely across the fire room and serves as an air and water tight partition to separate a boiler compartment A from the operators' compartment B, the latter being adapted for human occupancy at atmospheric pressure; it being in-

tended to supply air under pressure, by any suitable means, into compartment A for combustion purposes.

The oil burning equipment, which comprises burner and air register units, is positioned between the bulkhead 1 and the boiler front plate 5, certain operative parts of said burner unit projecting into the compartment B, as shown.

For illustrative purposes only, and not in any way restricting the invention, I have shown the oilburning equipment included in my co-pending application, Ser. No. 88,736, wherein the air register unit is shown as provided with a pressed steel frame having divided members 2 that are engaged by studs 3 with a ring 4 that is secured to the plate 5, said ring also carrying the usual Venturi ring 6. Members 2 extend forwardly to a disk 7 that is provided with slots 8 for pins 9 that project from curved vanes 10 which are housed within frame members 2, said vanes having lugs 11 by which they pivotally engage studs 3. The rotatable plate 12 has slots 13 which engage pins 9, said plate carrying a toothed sector 14 operatively connected with pinion 15, the latter having an operating shaft 16 with handle 17 for its manipulation. A burner tube 18, with the usual atomizer 19 and flame cone 20 entered within the register, has jacket 21, the latter being carried by a hollow casting 22, in which it is rendered air tight by a stuffing box 23, said casting being provided with a passageway for the shaft 16 and here a stuffing box 24 is employed to render the fit air tight between shaft 16 and its passageway. A radial web 25 supports one end of an expansion bellows 26, the flange 27 being clamped between said web and a ring 28 as with bolts 29, the other end of said bellows being provided with a flange 30 that is clamped between bulkhead 1 and a ring 31 as with bolts 32. As explained in the aforesaid co-pending application, the purpose of the expansion bellows is to absorb expansion and other distortions occurring between the bulkhead and boiler. Obviously, the expansion bellows will not be used in many installations, it being of prime importance, of course, that the burner used should make an air tight connection with said bulkhead. As shown in Fig. 2, the disk 7 is apertured for the reception of the reduced portion 33, and the rotatable plate 12, which is also apertured, has its bearing about a shoulder 34 upon said casting, said plate being provided with a cover 35. A cover plate 36 is shown as carried by bulkhead 1, 55

and having the observation doors 37 and lighting door 38.

As shown in Fig. 2 the end of the burner jacket 21, projecting into the operators' compartment 5 B, carries a housing 39 having a cover plate 40, a coupling yoke 41 being pivotally carried by said housing, as indicated at 42, and adapted to clamp the member 43 in the position indicated, said housing and member 43 being provided with 10 bores to permit the flow of the oil from a source of supply to the burner tube. It will also be noted that said member 43 is provided with an enlarged bore 44 to support one end of the burner tube 18, and that flap valve 45 is pivotally 15 supported within said housing 39 and another flap valve 46 is pivotally disposed exteriorly of said housing. Normally the aforesaid parts are in the positions indicated in Fig. 2, but when it is necessary to remove a burner tube the hand 20 screw 47 is manipulated so that said yoke 41 now assumes the position shown in Fig. 3, member 43 being uncoupled, and finally said burner tube is withdrawn from its jacket. In such instance the jacket 21, without the use of valves 45 and 25 46 would afford a free passage for water or gases in either direction past the bulkhead. Hence, the valve 45 will close by gravity against a seat 48, and thus the flow of water or gases from compartment A into compartment B is prevented. 30 As means of visual indication that valve 45 is closed, it being concealed in housing 39, said valve is provided with an exposed vertical lever 49 that assumes a prone position as said valve closes. Obviously, said lever may be operated 35 by hand to close said valve. The valve 46 is pivoted at 46a to the housing and is adapted to close against an outer seat 50 when the burner tube 18

is withdrawn, and thus prevent the flow of water or gases from compartment B to compartment A. In view of the foregoing it is obvious that the burner jacket is protected from pressure flow in either direction. 5

Variations within the spirit of the invention and scope of the claims are equally comprehended by the foregoing disclosure.

I claim:

1. The combination with oil burning equipment 10 including a burner jacket and a burner tube removably encased therein, of a housing engaging and in communication with said jacket at one end, said housing being provided with inner and outer valve seats, and valves adapted respectively 15 to engage said seats and close said jacket against pressure exerted in either direction when the burner tube is removed from the jacket.

2. The combination in a fire room having a bulkhead dividing it into a boiler compartment 20 and an operators' compartment in which substantially different pressures are maintained, of a hollow casting secured to said bulkhead and projecting into the boiler compartment, a burner jacket mounted and sealed within said casting 25 and projecting into the operators' compartment, a burner tube removably mounted within said jacket, a housing connected to one end of said jacket, said housing being provided with inner and outer valve seats, and valves hingedly connected to said housing and adapted respectively 30 to engage said seats and close the passage in said jacket against pressure exerted in either direction when the burner tube is removed from the jacket. 35

GEORGE P. HAYNES.
